(57) **CLAIM**

The ornamental design for a “beverage container crate”, as shown and described.

DESCRIPTION

FIG. 1 is a front, left, top perspective view of a beverage container crate in accordance with an exemplary embodiment of the invention;

FIG. 2 is a top plan view thereof;

FIG. 3 is a front elevation view thereof;

FIG. 4 is a left side elevation thereof, the right side elevation being identical thereto;

FIG. 5 is a bottom plan view thereof;

FIG. 6 is a front, left, top perspective view of a beverage container crate in accordance with another exemplary embodiment of the invention; and,

FIG. 7 is a front elevation view thereof, the remaining views being identical to the first exemplary embodiment.
